[57] CLAIM

The design for a combined lavatory cabinet and folding bathtub, as shown.

DESCRIPTION

FIG. 1 is a perspective view taken from the top, front and left side of a combined lavatory cabinet and folding bathtub showing my new design;

FIG. 2 is a top plan view thereof;

FIG. 3 is a right side elevational view thereof; and

FIG. 4 is a perspective view taken from the top, front and left side thereof showing the cabinet in an open position and the bathtub in its extended position.
